CLAIM

The ornamental design for a flip cover for mobile terminal, as shown and described.

DESCRIPTION

FIG. 1 is a front perspective view of a flip cover for mobile terminal showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an open rear perspective view, showing the inside of the flip cover thereof; and,

FIG. 10 is an open front perspective view, showing the outside of the flip cover thereof.
